UNITED STATES PATENT OFFICE.

OSCAR KORN, OF NEW YORK, N. Y.

TOY.

SPECIFICATION forming part of Letters Patent No. 652,786, dated July 3, 1900.
Application filed June 15, 1899. Serial No. 720,611. (No model.)

To all whom it may concern:

Be it known that I, OSCAR KORN, a citizen of the United States, residing at New York, in the county of New York and State of New York, have invented certain new and useful Improvements in Toys, of which the following is a full and complete specification, such as will enable those skilled in the art to which it appertains to make and use the same.

10 This invention relates to toys; and the object thereof is to provide an improved device of this class which is designed to amuse children and which comprises a pop-gun of novel construction and consisting of a barrel provided with a detached and movable piston-plug, an end plug having a flexible connection with said barrel, and a plunger-rod by means of which the piston-plug may be moved from one end of the barrel to the other, the 15 plunger-rod being shorter than the barrel, so that the piston-plug cannot in the operation of the device be forced out of the barrel.

20 The invention is fully disclosed in the following specification, of which the accompanying drawings form a part, in which—

25 Figure 1 is a side elevation of my improved pop-gun, the barrel, end plug, and piston-plug being shown in position and said barrel being shown in section; and Fig. 2, a view 30 similar to Fig. 1, showing the parts in a different position.

35 In the drawings forming part of this specification, the separate parts of my improvement are designated by the same numerals of reference in each of the views, and in the practice of my invention I provide a barrel 5, which may be of any desired length and composed of any desired material and in which is mounted or placed a piston-plug 6, 40 which is composed of cork or any preferred material and which closely fits the interior of the barrel 5. I also provide an end plug 7, which is composed of cork or any other suitable material and which is slightly conical in 45 form and adapted to be inserted into either end of the barrel, and said end plug 7 is connected with the barrel by a cord 8, which may be composed of elastic or any other suitable material. The cord 8 is preferably tied 50 around the middle portion of the barrel, as shown at 9, and is secured to the end plug 7 by a staple 10 or in any suitable manner. I

also provide a plunger-rod 11, having a handle 12, and said plunger-rod is adapted to be forced into the barrel from either end thereof. 55

In practice or in the operation of the device the piston-plug 6 is forced by the plunger-rod into one end of the barrel, as shown in Fig. 2. The plug 7 is then inserted and pressed tightly into the opposite end. The 60 plunger-rod 11 is then inserted into the end adjacent to which the piston-plug 6 is located, as shown in Fig. 1, and the said piston-plug is then forced quickly through the barrel by the plunger-rod. This operation forces out 65 the end plug 7 and causes a loud report similar to that of other devices of this class, the air in the barrel operating to produce this result.

The cord 8 may be of any desired length, 70 and the end plug 7 remains connected therewith, and the above-described operation may be repeated as often as desired.

It will be observed that the plunger-rod 11 is of such length that when forced entirely 75 into the barrel from one end it will not force the piston-plug 6 out of the other end, and said piston-plug is always in position for use, and the end plug 7 is placed alternately in the opposite ends of the barrel and the plunger-rod 11 correspondingly alternately used 80 from either end.

This device is simple in construction and also inexpensive and well adapted to accomplish the result for which it is intended. 85

Having fully described my invention, I claim as new and desire to secure by Letters Patent—

1. A device of the class described, comprising a barrel, an independent movable piston-plug which operates within said barrel and in the operation of the device is not removed therefrom, independent means for operating said piston-plug, and an independent end plug which in the operation of said device is inserted alternately into the ends of said barrel, substantially as shown and described. 90

2. A device of the class described, comprising a barrel, a plunger-rod shorter than said barrel and provided at one end with a handle 100 by which the extent of insertion of said plunger-rod into said barrel is limited, a movable independent piston-plug which operates within said barrel and the path of motion of which

is shorter than said barrel, and an independent end plug which in the operation of said device is inserted alternately in the ends of said barrel, substantially as shown and described.

5 In testimony that I claim the foregoing as my invention I have signed my name, in pres-

ence of the subscribing witnesses, this 13th day of June, 1899.

OSCAR KORN.
